S. GARDINER, Jr. & L. BLOSSOM.

Electric-Signal Light.

No. 20,706.

Patented June 29, 1858.

UNITED STATES PATENT OFFICE.

S. GARDINER, JR., AND L. BLOSSOM, OF NEW YORK, N. Y.

IMPROVED ELECTRIC SIGNAL-LIGHT.

Specification forming part of Letters Patent No. 20,706, dated June 29, 1858.

To all whom it may concern:

Be it known that we, SAM'L. GARDINER, Jr., and LEVI BLOSSOM, of the city, county, and State of New York, have invented a new and useful Electric Signal Lantern or Light; and we do hereby declare that the following is a full, clear, and exact description of the same, reference being had to the accompanying drawings, forming a part of this specification, in which—

Figure 1 is a front view of a signal lantern or light constructed after our invention. Fig. 2 is a vertical longitudinal section of the same. Fig. 3 is a vertical transverse section of the same. Fig. 4 is a diagram illustrating a modification of our invention.

Similar letters of reference in each of the several figures indicate corresponding parts.

The nature of our invention consists in the combination of a platinum coil or its effective equivalent, which is illuminated by electricity, with a transparent signal-lantern, said combination being effected by arranging the coil within the lantern upon two conducting-wires which are connected with an electro-galvanic battery.

To enable others skilled in the art to make and use our invention, we will proceed to describe its construction and operation.

A represents a standard for supporting a signal-lantern, B, adapted for carrying out our invention successfully. This lantern has two or more of its sides formed of colored glass, one side being blue and the other red, or otherwise illuminated so as to be seen readily at a great distance. The central portion of the transparent sides is not colored, as shown at a, so that the intense light directly about the platinum coil may not be shaded, or be partially obscured. The lantern is provided with suitable reflectors, b b, and is ventilated by means of holes c c and spaces d d around the edges of the glass, as illustrated by the arrows.

O is the platinum coil. It should have the form of a circle and be arranged opposite the central uncolored portions, a a, of the glass sides, as shown. This coil rests upon two conducting-wires, D D, which extend down from the interior of the lantern to the battery, which is situated in the lower or any convenient part of the hull of the vessel, and is connected with a telegraphing-machine, so that the electric

illuminating-current may be let onto the platinum coil or shut off from it at pleasure.

Instead of having the conducting-wires extend down to the battery, they may be cut off so as to just touch the base-plate d of the standard of the lantern. In this case said plate must be connected with the battery and be insulated at two points on its surface, in the manner shown at e e, Fig. 4, and the lantern and standard arranged to revolve.

By our invention the most intense and brilliant light can be constantly kept up, as the electric current is concentrated by the platinum coil in a manner that said coil will always be heated to the color of a brilliant white flame, which will be seen at a great distance through the unshaded central part of the lantern, and its reflected rays through the colored portions of the transparent front.

With our invention any desired signals may be transmitted from one ship to another, as follows: We will suppose that the captains of different ships have agreed between themselves that the appearing and disappearing of the signal-light twice shall indicate "distress," the appearing and disappearing of the light three times, "all right," and so on. Now, to accomplish these signals all that is necessary is for the captain or other person in charge of the matter to touch the keys of the telegraphing-machine, the proper number of times and in the proper manner.

In case the signal-lantern is arranged to revolve, the same signals can be produced by the breaking of the current at intervals, which is effected by having the conducting-wires come at intervals in contact with the insulated portions of the base-plate.

The signal-lantern has two of its sides formed of different-colored glass, so that when used on a buoy the electric light may be seen by ships coming in and going out to sea.

The value of a sure signal-light cannot be estimated when the important office it is to serve is considered. We believe our signal-light can be depended upon, both as to its great intensity and as to its certainty of remaining always in force, there being no possible chance for it to cease so long as the battery is supplied and the electric current conducted to the platinum coil.

This invention is perfectly applicable to the

purpose of signal-lights on board of boats, ships, vessels, and buoys; also to stationary signals on land for military and scientific purposes; also for all stationary or floating light-houses for coasts and harbors.

What we claim as our invention, and desire to secure by Letters Patent, is—

The combination of a platinum coil, C, or its effective equivalent, which is illuminated by electricity, with a transparent signal-lan-

tern, B, said combination being effected by arranging the coil C within the lantern B upon two conducting-wires, D D, which are connected with an electro-galvanic battery.

SAMUEL GARDINER, JR.
LEVI BLOSSOM.
